Henry G. Thompson of New York No. 9. DES. 2402

Assignor to

The Hartford Carpet Co. of Hartford Ct.

Letters Patent No. 3442, Dated Aug. 14. 1866.

Design for a Carpet Pattern.

The Schedule referred to in these Letters Patent and making part of the same.

To all whom it may concern,

Be it known that I, Henry G. Thompson of the City of New York and State of New York have invented or produced a new and original Design for a Pattern to be wrought into two-ply, Ingrain and other carpeting in colors similar to those painted on the drawings accompanying this Specification, or in other colors substituted in the place of those painted on the drawings herewith; and I do hereby declare that the drawings accompanying this Specification, do give and convey to anyone skilled in the art of carpet weaving a more defined and thorough description of the nature of my invention than it is in the power of language otherwise to convey, and is sufficient to enable anyone skilled in the art of carpet weaving to use my invention.

What I claim as my invention and desire to secure by Letters Patent is,

The configuration of the Design herunto annexed when made by being wrought into two-ply Ingrain or other carpeting in the form similar to the drawings accompanying this Specification.

Witnesses.

John G. Malkin.
